H. T. McGOWAN,
ATTACHMENT FOR THE PLATES OF ARTIFICIAL TEETH.
APPLICATION FILED MAY 10, 1915.

1,159,971.

Patented Nov. 9, 1915.

UNITED STATES PATENT OFFICE.

HERBERT THOMAS McGOWAN, OF PRAHRAN, VICTORIA, AUSTRALIA.

ATTACHMENT FOR THE PLATES OF ARTIFICIAL TEETH.

1,159,971.

Specification of Letters Patent.

Patented Nov. 9, 1915.

Application filed May 10, 1915. Serial No. 27,161.

To all whom it may concern:

Be it known that I, HERBERT THOMAS McGOWAN, a subject of the King of Great Britain and Ireland, and a resident of 5 Prahran, in the county of Bourke, State of Victoria, Commonwealth of Australia, (whose post-office address is 326 Malvern road, in the said city of Prahran,) have invented certain new and useful Improvements 10 in Attachments for the Plates of Artificial Teeth, of which the following is a specification.

This invention relates to artificial teeth carried by a plate and pertains to those 15 cases where the patient possesses natural teeth in conjunction with which the plate is worn. Hitherto it has been usual for the plate to be supported or bear against the gums of the mouth with the result that very 20 accurate fitting is essential to the wearer's comfort and in time the gums shrink causing discomfort and sometimes necessitating a new plate. Without special treatment it is also impracticable to provide a person 25 with a plate which can be worn in comfort before the gums have healed after extraction of the natural teeth. Further, a person can but rarely use artificial teeth effectively for some considerable time after fitting, when 30 carried by a plate, owing to the un-natural pressure of the plate upon the gums.

The object of this invention is to provide for the relief or removal of the pressure of the plate upon the gums and to communicate 35 the said pressure to the natural teeth. By the invention, further, a plate need not bear closely against the gums as hitherto, shrinking of the gums being thereby reduced to a minimum. Still further the extreme accuracy 40 previously required in fitting a plate is not necessary and a patient may wear a plate sooner after extraction of his natural teeth. The use of the artificial teeth is also increased as pressure applied in use is 45 greatly absorbed by the natural teeth.

Referring to the drawings which form part of this specification—Figure 1 is an enlarged sectional view of an attachment according to the invention. Fig. 2 is a front elevation of Fig. 1. Fig. 3 is a sectional plan of Fig. 2 taken on line A—A. Fig. 4 is a rear elevation of Fig. 1. Fig. 5 is a detail view showing a modified anchor of the attachment. Fig. 6 is a sectional plan of 55 Fig. 5, taken on line B—B. Fig. 7 is a rear elevation of an attachment showing a

further modification. Fig. 8 is a plan of Fig. 7. Fig. 9 is a perspective view showing a lower jaw plate carrying artificial teeth and a plurality of attachments for suspending the plate to the natural teeth remaining in the jaw. In the view a series of recesses to accommodate the natural teeth are seen between the attachments. Fig. 10 is a perspective view showing the plate seen 60 in Fig. 9 suspended to the natural teeth. Fig. 11 is a front elevation of an attachment having a plurality of caps. Fig. 12 is a sectional view of Fig. 11, taken on line C—C. Fig. 13 is a front elevation of an attachment 65 having a plurality of connecting portions. Fig. 14 is a sectional view of Fig. 13, taken on line D—D. Fig. 15 is a sectional plan taken on line E—E. Fig. 13, showing the anchor of one of the connecting portions. 75

The invention is only useful in those cases where the patient possesses some natural teeth and is inapplicable to those cases where all of the natural teeth have been extracted.

In the drawings natural teeth are indicated by 2. Within the mouth is a plate 3, of any ordinary nature. The plate carries artificial teeth 4 disposed between the natural teeth 2.

The invention consists (Figs. 1 to 10) in 85 an attachment having a connecting portion 5 the inner end of which is provided with an anchor whereby it is retained to the plate 3. The anchor may consist of an out-turned tongue 6. Or a plurality of opposed tongues 90 7 may be provided, the number and position of the tongues depending upon the position of the attachment with regard to the plate. Instead of tongues being used the anchor 95 may consist of a curved pin 8 having out-turned ends 9.

The outer end of the connecting portion 5 is integral with the side 10 of a cap having a crown 11. The number of attachments carried by a plate will depend upon circumstances. The height of the side of the cap of each attachment will also vary with circumstances. It may, if desired, envelop the whole of a tooth above the gum. Each attachment is preferably cast in gold but may 105 be formed in any other way and from any suitable material. Instead of a single cap being provided with each attachment a plurality of caps may be employed, as seen in Fig. 11. A division wall 12 may then depend from the crown of the attachment separating each cap from its fellow. The an-

chor may also be formed by expressed tongues 13 which may be opposed or disposed in opposite directions. When an attachment is used in conjunction with a molar 5 or large tooth the said cap consists of an outer side 14, an inner side 15, an outer end 16, and an inner end 17. Extending between the sides and ends is a crown 18 conforming to the conformation of the top of the tooth. 10 The outer side 14 may have portion thereof removed (Fig. 13) as indicated at 19, in order that as little gold as possible will be seen. Integral with the inner side 15 are the outer ends of a plurality of connecting portions 20 each having an inner end provided with an anchor. Each anchor may consist of a plurality of out-turned opposed tongues 21.

With this invention, as shown in Fig. 10, a plate is provided with a series of attachments 20 each having a cap adapted to fit or seat upon a natural tooth. The invention is particularly intended for use with lower jaw plates but may be used with upper plates also as in either case it may prevent the plate 25 from pressing closely upon the gums. In use pressure is absorbed by the attachment and the natural teeth. It will be apparent to those skilled in the art that an attachment may have a series of caps thereto and anchors of varying description. It will also be apparent that the extent to which a natural tooth is enveloped by the cap of an attachment will depend upon the circum-

stances surrounding each individual case and upon the taste of the wearer or patient. 35

Having now described my invention what I claim as new and desire to secure by Letters Patent is:—

1. An attachment for plates of artificial teeth comprising a cupped portion, which is 40 adapted to fit over the top of a natural tooth one side of cupped portion being extended to form an attaching means for the plate.

2. An attachment for plates of artificial teeth comprising a cupped portion which is 45 adapted to fit over the top of a natural tooth and a plate attaching portion, the plate attaching portion being provided with a plurality of anchoring spurs.

3. Improvements in attachments for the 50 plates of artificial teeth, consisting in the combination of an attachment having means for securing the same to the plate and a cap carried by the said attachment.

4. An attachment for the plates of artificial teeth consisting in the combination of a connecting portion having an anchor at its inner end and a cap at its outer end. 55

In testimony whereof I have hereunto affixed my signature in the presence of two 60 subscribing witnesses.

HERBERT THOMAS McGOWAN.
